B. HORVATH ET AL

AMUSEMENT DEVICE

Filed Jan. 12, 1924

INVENTORS

BY *Julian J. Wittel*

ATTORNEY

UNITED STATES PATENT OFFICE.

BELA HORVATH AND JOHN PETZ PAPP, OF NEW ROCHELLE, NEW YORK.

AMUSEMENT DEVICE.

Application filed January 12, 1924. Serial No. 685,804.

To all whom it may concern:

Be it known that we, BELA HORVATH and JOHN PETZ PAPP, citizens of Czechoslovakia and the United States, respectively, and residents of New Rochelle, in the county of Westchester and State of New York, have invented certain new and useful Improvements in Amusement Devices, of which the following is a specification.

10 Our invention relates in general to amusement devices, and more particularly to amusement devices of the type wherein representations of animals or other objects are automatically actuated to serve as targets for marksmen or to afford features of display and amusement.

15 A main object of our invention is to provide a power driven device of the character specified, embodying mechanism by which likeness or representations of animals or other objects are made automatically to appear and disappear either for affording a practice target for sportsmen or marksmen or for affording a moving display or source 25 of amusement.

20 Another object of our invention is the provision of a simply constructed, inexpensive and efficient device of the character specified, adapted to be used at fairs and summer resorts, in shooting galleries, entertainment halls and other places of public amusement.

25 Still a further object of this invention is to provide a device of the mentioned characteristics which may be operated with a minimum use of outside energy showing a well balanced and even running and very little resistances and losses, frictional or otherwise.

30 With these and other objects in view, our invention embodies the peculiar construction and novel arrangement of parts hereinafter described and pointed out in the appended claims.

35 The figure in the accompanying drawing represents a front perspective view of a device constructed in accordance with our invention, the device being shown in a diagrammatic manner and without any casing or protecting sheathing in order to exhibit fully the internal mechanism.

40 In carrying out our invention, we preferably employ as primary supporting frame parts the side uprights 5 which have their

lower ends bent outwardly at right angles to 55 constitute feet 6. In practice we employ so many of these uprights as may be necessary for the firm and adequate support of the structure, the same being arranged in circular series or order, but in the present drawing we show but two of these uprights which are connected adjacent the feet 6 by a cross-piece 7 and a distance thereabove by a cross-piece 8. Adjacent their top ends, these uprights are furnished with inwardly projecting angular brackets 9 between which is fixedly supported a vertical ring plate or track 10, thereby securely connecting the top portions of the uprights.

45 Secured to the cross-piece 7, midway its 70 length, is a vertical bearing 11, in which is journaled the lower end of a vertical shaft 12. The cross-piece 8 is also provided with a bearing 13 for the vertical shaft 12 which continues upwardly for the support of a 75 saddle plate 14 made with oppositely directed arms 15 each carrying a vertical guide block 16. A distance above the bearing 13, a belt pulley 17 is loosely mounted on the vertical shaft 12. This belt pulley is provided on the one side with equi-spaced radially projecting arms 18, to the outer ends of which is secured a cam ring or track 19, having spaced depending hangers 20 carrying flanged rollers 21 which are supported 80 upon a vertical ring plate or track 22, secured on the cross-piece 8. The cam track 19 is thus mounted to rotate upon ring track 22 and about the vertical shaft 12, which serves as an axis and which, as will herein- 85 after appear, is independently rotated.

90 23 denotes a scenic ring from which all around projects upwardly an irregular or jagged formation 24 in imitation of a landscape or other scenic views, the formation 95 24 being exteriorly painted or otherwise ornamented to represent rocks, hills, woodland or other scenery. This scenic ring 23 is provided with spaced-apart depending hangers 25, carrying flanged rollers 26 100 adapted to travel upon the ring track 10. In this manner the scenic ring is mounted for rotation at the top of the structure.

105 Engaged in each of the guide blocks 16 is a vertical reciprocating bar 27 provided at its lower end with an outwardly directed stud or shaft 28, carrying a heavy wheel 29, relatively large in size as shown, with out-

bulging sides and having flanges to travel upon the cam track 19. It will be observed that the parts are so arranged that the top ends of the reciprocating bars 27 come interiorly of the scenic ring 23 and that to the top end of each of these bars there is secured for swinging movement upon a pivot stud 30 the likeness or representation of an animal 31. In order to swing each of the 10 animals on its axis to give effect of a jumping or leaping movement, we employ a connecting or pitman rod 32 which pivotally connects the symbol of the animal with the wheel 29 immediately below. Now, the ring 15 cam 19 is made with a deep indenture to provide a low edge or track 33 from which on one side is a slow incline 34 leading to the high edge 35, and on the other side an abrupt descent 36, leading from the high 20 edge, so that when the vertical shaft is rotated the wheels 29 will travel upon the cam track rising and falling as they traverse the high and low edges of the track. The excessive weights of the wheels 29 will 25 also preserve and distribute the comparatively small momentums given our structure by the outside source of energy, and they will impart an even, sustained and easy motion to our device. As the wheels revolve 30 upon the cam track the animals are swung upon their axes and at the same time, while pursuing their circuitous course, the animals rise and fall in response to the irregularities of the cam track. Hence the animals 35 are given three distinct movements interiorly of the landscape formations—they move in a circular path because of the rotation of the vertical shafts 12, they are swung on their axes because of the rotation 40 of the wheels 29, and they are elevated and lowered because of the irregularities of the cam track.

The vertical shaft 12 is provided with a bevel gear 37 which is driven by a bevel 45 gear 38 on a shaft 39 of the electric motor 40. The motor shaft 39 on its opposite end, exteriorly of an upright 5, carries the bevel gear 41 in mesh with another bevel gear 42, fast on the end of a vertical shaft 43 50 operatively held in bearings 44 and 45 supported from an upright 5. The cam track is driven by a belt 46 which connects the wheel 17 with a pulley 47 fast on the shaft 43, and it will be noted in this connection 55 that because of the arrangement of the bevel gears the cam track 19 will be driven in a direction opposite to that given to the vertical shaft 12. The scenic ring 23 is provided with a relatively thick periphery 60 48 with which a friction disc 49 engages for the purpose of imparting rotary movement to this ring. The friction disk 49 is secured to the upper end of the vertical shaft 43. The vertical shaft 12, the cam track 19 and 65 the scenic ring 23 are, therefore, all driven

independently from the same source of power.

Having thus described our invention, what we claim is:

1. In an amusement device, the combination with a cam ring, and a scenic ring and means for supporting them, of a vertical shaft arranged centrally of the cam ring and provided with arms above said cam ring, guide blocks carried by said arms, wheeled bars having reciprocating movement in said guide blocks the wheels for said bars being comparatively heavy and adapted to travel on said cam ring, the upper ends of said bars extending interiorly of said scenic ring and provided with pivotally engaged animal representations, pitman connections between said wheels and said animal representations to swing the latter on their axes when said wheels revolve on the cam ring, and means for rotating said vertical shaft.

2. In an amusement device, the combination of a cam ring and a scenic ring and means for rotatably supporting them, a vertical shaft arranged centrally of the cam ring and provided with arms thereabove, guide blocks carried by said arms, bars engaged in said blocks for vertical reciprocating movements, flanged wheels carried by said bars and engaged with said cam ring to travel thereon, animal symbols pivotally engaged with the upper ends of said bars interiorly of the scenic ring, pitman connections between said wheels and said animal symbols to swing the latter on their axes when said wheels rotate upon the cam ring, and means for driving said cam ring, said scenic ring, and said vertical shaft.

3. In an amusement device, the combination with upper and lower track rings and means for supporting them, of a wheeled cam ring rotatably mounted upon the lower track ring, a wheeled scenic ring rotatably mounted upon the upper track ring, a vertical shaft arranged centrally of the cam ring and provided with arms thereabove, guide blocks carried by said arms, bars engaged in said blocks for vertical reciprocating movements, flanged wheels carried by said bars and engaged on said cam ring to travel thereon, symbolic characters pivotally engaged with the upper ends of said bars interiorly of the scenic ring, pitman connections between said wheels and said symbolic characters to swing the last mentioned on their axes when said wheels rotate upon the cam ring, and means for independently rotating said cam ring, said scenic ring and said vertical shaft.

4. In an amusement device, the combination with a scenic ring of a cam ring mounted rotation in axial relation therewith, a vertical shaft supported for rotation centrally of the cam ring and provided with

arms thereabove, guide blocks carried by said arms, bars engaged in said blocks for vertical reciprocating movements, the upper ends of said bars extending interiorly of 5 said scenic ring, flanged wheels carried by said bars and engaged with said cam ring to rotate thereon, symbolic characters pivotally mounted upon the upper ends of said bars, pitman connections between said symbolic characters and said wheels to swing 10

said symbolic characters upon their axes when said wheels rotate, and means for driving said cam ring, and said vertical shaft in opposite directions.

Signed at New York in the county of ¹⁵ New York and State of New York this 22nd day of December A. D. 1923.

BELA HORVATH.
JOHN PETZ PAPP.
